UNITED STATES PATENT OFFICE.

FREEMAN KEENE GALE, OF SARATOGA SPRINGS, NEW YORK.

DESIGN FOR A TRUCK-BRACE.

SPECIFICATION forming part of Design No. 22,915, dated November 21, 1893.

Application filed October 6, 1893. Serial No. 487,381. Term of patent 7 years.

To all whom it may concern:

Be it known that I, FREEMAN KEENE GALE, a citizen of the United States, residing at Saratoga Springs, in the county of Saratoga and State of New York, have invented a certain new and useful Design for a Truck-Brace, of which the following is a specification.

In the accompanying drawings Figure, 1 is a plan view showing my new design for a truck brace. Fig. 2, is a side view of the same.

My design for a truck brace includes as its essential features two arms, *a*, *a*, each of which terminates in an eye *i*, the arms being curved 15 converging inwardly, meeting at the neck *b*,

where they merge together and from which neck extend two bent portions *c*, *c*, each of which is tapered and bent or curved both outwardly and downwardly.

What I claim is—

The design for a truck brace, substantially as shown and described.

In testimony whereof I have signed my name to this specification in the presence of two subscribing witnesses.

FREEMAN KEENE GALE.
